Primary Examiner — Cynthia Ramirez(74) *Attorney, Agent, or Firm* — K&L Gates LLP(57) **CLAIM**

The ornamental design for a winch, as shown and described.

DESCRIPTION

FIG. 1 is a front perspective view of a winch showing our new design.

FIG. 2 is a front view of the winch of FIG. 1.

FIG. 3 is a back view of the winch of FIG. 1.

FIG. 4 is a left side view of the winch of FIG. 1.

FIG. 5 is a right side view of the winch of FIG. 1.

FIG. 6 is a top view of the winch of FIG. 1; and,

FIG. 7 is a bottom view of the winch of FIG. 1.

The broken lines in FIGS. 1-7 are included for the purpose of illustrating environmental structure and form no part of the claimed design.
